UNITED STATES PATENT OFFICE.

ORVILLE M. MORSE, OF JACKSON, MICHIGAN, ASSIGNOR TO THE KNICKER-BOCKER COMPANY, OF SAME PLACE.

DUST-COLLECTOR.

SPECIFICATION forming part of Letters Patent No. 370,021, dated September 13, 1887.

Original application filed June 9, 1886, Serial No. 204,684. Divided and this application filed August 22, 1887. Serial No. 247,540.
(No model.)

To all whom it may concern:

Be it known that I, ORVILLE M. MORSE, of the city of Jackson, in the county of Jackson and State of Michigan, have invented a new 5 and useful Improvement in Dust-Collectors, of which the following is a specification.

This invention relates to a dust-collector which is provided with a conical or tapering separating-chamber, into which the dust-laden air is delivered from a tangential inlet-spout, whereby the air is caused to assume a whirling or gyrating motion in the separating-chamber. This motion of the air causes the solid particles to pass into the outer layer of the 15 whirling body of air and to be deposited against the inner surface of the separating-chamber, which latter is provided with a discharge-opening for the separated dust and an escape-opening for the purified air. A dust-collector 20 of this kind is described and claimed in an application for patent filed by me March 31, 1886, Serial No. 197,307. It is found in practice that the fine and light dust follows the tapering wall of the separating-chamber toward the 25 small end thereof, while larger bulky particles of the size of a kernel of grain and larger move under the influence of centrifugal force in an opposite direction toward the large end of the separating-chamber.

30 The object of my present invention is to construct the dust-collector in such manner that the large solid particles are freely discharged from the separating-chamber; and my invention consists to that end of the improvements which 35 will be hereinafter fully described, and pointed out in the claims.

In the accompanying drawings, Figure 1 is 40 a sectional elevation of my improved dust-collector. Fig. 2 is a top plan view thereof on a reduced scale. Fig. 3 is a horizontal section in line $x-x$, Fig. 1, on a reduced scale. Fig. 4 is a longitudinal vertical section through the dust-discharge passage at the large end of the separating-chamber.

45 Like letters of reference refer to like parts in the several figures.

A represents the stationary frame of the machine, and B the conical or tapering separating-chamber supported in the same.

C represents the spout through which the 50 dust-laden air enters the large end of the chamber B in a tangential direction.

d represents the discharge-opening for the fine or light dust, formed at the apex or small end of the tapering chamber B. 55

E represents the cover or head which closes the large end of the chamber B, and which is provided with a large central opening, e, through which the purified air escapes from the machine. 60

f is a tubular guard secured to the head E in the opening e.

g represents the discharge-passage for the large or heavy dust or material, arranged at the periphery of the large end of the tapering 65 separating-chamber. This passage is preferably formed by a recess cut into the under side of the head E, as represented in Figs. 1 and 4, and extending outwardly from the interior of the chamber B to the outer side of the head, 70 as represented by dotted lines in Fig. 2. The outer end of the passage g connects with a descending spout, G, by which the heavy material is conducted to a suitable receptacle.

The dust-laden air enters the tapering chamber E in a tangential direction and assumes a whirling or gyrating motion in the same, forming a vortex in which the dust particles are quickly driven to the periphery of the whirling body of air, thereby freeing the inner portion of the whirling body of air from dust. The fine and light dust particles move in helical lines of gradually-decreasing radius toward the small end of the tapering chamber B and escape finally through the opening d. The 75 large and heavy particles move in helical lines of gradually-increasing radius toward the large end of the tapering chamber B and escape finally through the passage g. The air which has been freed from dust escapes through the opening e, which is protected by the depending tubular guard f. The latter prevents dust particles, which have just entered the chamber B by the spout C, from passing into the outgoing current of purified air and escaping 80 with the same. 85

I do not wish to claim in this application the combination of the tubular guard with

the separating-chamber, as this invention is claimed in an application filed by me June 9, 1886, Serial No. 204,684, of which the present application is a subdivision.

5 I claim as my invention—

1. In a dust-collector, a tapering separating-chamber provided with an external inlet-spout entering the case tangentially, a discharge-opening for the escape of the heavy solid matter, arranged at the large end of the separating-case, and a central air-exit, substantially as set forth.
2. In a dust-collector, a tapering separating-chamber provided with an external inlet-spout entering the case tangentially, a discharge-opening at the large end of the case for the escape of the heavy solid matter, a discharge-opening for the light dust, and a central air-exit, substantially as set forth.
- 15 3. In a dust-collector, a tapering separating-

case provided at its apex with an opening for the escape of the light material and at its large end with a central opening for the escape of the purified air and a peripheral opening for the escape of the heavy material, and 25 means whereby the air is caused to whirl in the separating-case, substantially as set forth.

4. The combination, with the conical separating-chamber B, having a discharge-opening, *d*, at its apex, and a tangential air-inlet 30 spout, C, of a head, E, provided with a central opening, *e*, and a recessed peripheral opening, *g*, substantially as set forth.

Witness my hand this 17th day of August, 1887.

ORVILLE M. MORSE.
